UNITED STATES PATENT OFFICE.

JOSEPH P. MILLER, OF BOSTON, MASSACHUSETTS.

SOFA-BED.

SPECIFICATION forming part of Letters Patent No. 395,247, dated December 25, 1888.

Application filed April 25, 1888. Serial No. 271,835. (No model.)

To all whom it may concern:

Be it known that I, JOSEPH P. MILLER, of the city of Boston, in the county of Suffolk and State of Massachusetts, have invented certain 5 new and useful Improvements in Sofa-Beds, of which the following is a full, clear, and exact description.

This invention relates to sofa-beds in which the back is hinged to the seat to be placed in 10 a vertical position to serve as a back to the seat and in a horizontal position to serve with the seat as a bed, means being provided to secure it in either position, all as well known.

This invention consists of a support of the 15 back in a horizontal position, composed of a leg (preferably one at each of its ends) which at one end is suspended by a pin from and to turn in and travel along a slotted way of and running at right angles to the length of the 20 back, in combination with two parallel links or bars, each jointed at one end to opposite points in the length of the leg and at their other end to the seat-frame or a stationary part thereof, and all in a manner to secure in 25 the lowering of the back a swing of the leg into position at right angles to the back, and thus a position of a support thereto, and in the lifting of the back a swing of the leg toward and, as it were, to fold it against the 30 back; and, in combination with the above, the invention also consists of a support for the back in its vertical position, composed of a sliding bolt fixed to the back and arranged for an engagement with said slotted way and 35 engaged to act as a stop to the travel of the connection of said leg-support for the back along said way; and, again, the invention consists of a spring applied to the link-connection of the leg with the back to assist in rais- 40 ing the back from a horizontal to a vertical position.

In the drawings forming part of this specification, Figure 1 is a back elevation of the sofa-frame, not upholstered. Fig. 2 is a 45 transverse vertical section, line 2-2, Fig. 1. Fig. 3 is a section similar to Fig. 2, with the back in a horizontal position; Figs. 4, 5, and 6, detail views.

In the drawings, A represents the seat-frame of a sofa, B B the arm-frames at opposite ends of the seat-frame, and C the back-

frame, all, except as to the features of this invention, as ordinary and well known.

The back-frame C, at one end along its under edge, C², is hinged to the rear edge, A², of 55 the seat-frame A, and at each end it has a section or wing, C³, made separate from and hinged to it to make with the back in its vertical position continuations thereof at and across the rear of the arm-frames B B, and 60 with the back in its horizontal position to serve as continuations of the arm-frames across the width of the back-frame, having first been suitably raised and supported therefor, as will hereinafter appear. 65

D D are legs, one at the opposite ends of the central portion of the back and for the support of the back when it has been lowered to a horizontal position to serve with the seat as a bed. The legs are joined by a rail, D². 70 Each leg D, at one end, has a pin, a, which enters a slotted way, b, extending at right angles to the length of the back, and each leg, at opposite points in its length, has one end of parallel links or bars E E² pivoted or 75 hinged, as at d, to it, and these links, at their opposite ends, are pivoted or hinged, as at f, to the seat-frame or other suitable stationary part of the sofa.

In raising the back to a vertical or lowering 80 it to a horizontal position, each leg D, by its pin a, travels along and turns in the slotted way b of the back, and the links or bars E E² swing by their pivots or hinges at d f on the leg and seat-frame, and thus in the lifting of 85 the back-frame the legs are moved to a position of fold, as it were, against the back, and in the lowering of the back-frame the legs are moved to a position to serve as leg-supports to the back-frame. 90

H H are spring slide-bolts, of any ordinary or other suitable construction, located at the opposite ends of the central portion of the back-frame, and each in position to be engaged with the slotted way b of the back-frame at the corresponding end and just above the pin a of the leg-support, engaging said way when the back is in its vertical position. The bolts H, engaged as stated, restrain and hold the legs against travel along the slotted 95 way with which each is engaged, as described, and thus the back is made secure in its ver- 100

tical position. The release of the slide-bolts, as is obvious, sets the back free to be lowered to a horizontal position, and, preferably, the bolts are connected by a common cord, K, 5 passing through guide-eyes L of the back-frame, so as to be released by simply pulling on said cord, as well known in other sofa, lounge and similar beds.

Each hinged end wing, C³, of the back-frame C contains a fixed block projection, M, having a more or less rounded or cam-shaped edge, M², to run and bear upon the upper edge, N², of a stationary block, N, which is secured to the seat-frame, and its said edge 15 is at a height such as to secure, from the running thereon of the projecting block of the end wing of the back as the back is lowered to a horizontal position, the lifting of the end wing into a position of continuation of the sofa-arm at the corresponding end of the sofa. 20

O is a wire spring with a bend, P, having legs, each continued in a coil, Q, at right angles to its length, and having a free end, R. Each link-bar E² of the leg-connection with 25 the seat-frame has a spring, O, arranged to press by its bend against it. The coils Q of each spring O surround and are confined on a separate cross-bar, S, of and between ear-pieces T, which are secured to the seat-frame 30 or other suitable stationary part, and the free end R of each spring, for the effective action of the spring, as well known, is confined against a rest, U, of the ear-pieces. The springs O assist in the raising of the back, 35 and are used more particularly for that purpose, although, as is obvious, they act also as braces to the hinge-connection of the links or bars E², upon which they press with the seat-frame.

40 The connection-pin *a* of each leg D has a peripheral flange, *g*, Fig. 4, to allow the pin to engage and interlock with the edges of the slotted way *b*, in which it travels, and thereby prevent accidental disengagement of the pin 45 from the way. Again, each end of the slotted way *b* has a depression, *h*, (only one end shown, Fig. 2,) for the seating therein of the connection-pin *a* between it and the legs D. The engaging end of each sliding bolt H is 50 beveled off on one side, similar to a latch-bolt, to allow the connection-pin *a* of the leg D, as it travels along its slotted way *b* in raising

the back-frame, to freely force the sliding bolt back and out of its path.

All parts of the frames herein described, as 55 well known, are to be upholstered.

Having thus described my invention, what I claim, and desire to secure by Letters Patent, is—

1. In a sofa, lounge, &c., having the back-frame hinged to the seat-frame, a support for the back-frame in a horizontal position, composed of a leg, D, a guideway, *a*, of and across the length of the back-frame, and having said leg connected to it to turn in and travel along 60 it, and links or bars E E², pivoted or hinged at their opposite ends to opposite points in the length of said leg and to a stationary support, substantially as described, for the purpose specified.

2. In a sofa, lounge, &c., having the back-frame hinged to the seat-frame, a support for the back-frame in a horizontal position, composed of a leg, D, a guideway, *a*, of and across the length of the back-frame, and having said leg connected to it to turn in and travel along 65 it, and links or bars E E², pivoted or hinged at their opposite ends to opposite points in the length of said leg and to a stationary support, substantially as described, for the purpose specified.

3. In a sofa, lounge, &c., having the back-frame hinged to the seat-frame, a support for the back-frame in a horizontal position, composed of a leg, D, a guideway, *a*, of and across the length of the back-frame, and having said leg connected to it to turn in and travel along 70 it, and links or bars E E², pivoted or hinged at their opposite ends to opposite points in the length of said leg and to a stationary support, in combination with a bolt, 75 H, of the back-frame, to engage said guideway above the connection of leg therewith when the back-frame is vertical, substantially as described, for the purpose specified.

4. In a sofa, lounge, &c., having the back-frame hinged to the seat-frame, a support for the back-frame in a horizontal position, composed of a leg, D, a guideway, *a*, of and across the length of the back-frame, and having said leg connected to it to turn in and travel along 80 it, and links or bars E E², pivoted or hinged at their opposite ends to opposite points in the length of said leg and to a stationary support, and a spring, O, arranged to press on the link-bar E², substantially as described, for the 85 purpose specified.

In testimony whereof I have hereunto set my hand in the presence of two subscribing witnesses.

JOSEPH P. MILLER.
